UNITED STATES PATENT OFFICE

RALPH F. KIEFER, OF PITTSBURGH, AND JOHN P. RITCHIE AND ROBERT J. FARRELL, OF ELLWOOD CITY, PENNSYLVANIA, ASSIGNEES TO STROWAN CORPORATION, OF NEW YORK, N. Y., A CORPORATION OF DELAWARE

NAIL-MAKING MACHINE

Application filed August 28, 1928. Serial No. 302,450.

The invention relates to nail making machinery, and especially to cut-off mechanism for severing the nail stock during the tip-forming operation.

5 An object of the invention is to provide means separate from the tip-forming dies of a nail-making machine for cutting lengths of headed wire from the nail stock in suitable coordination and synchronism with the other 10 operations of the machine.

Still other objects are to provide nail severing mechanism of the type referred to whose action is simply and readily coordinated with that of the tip-forming dies, which is of 15 simple and readily applied construction, simple in operation, efficient, requires no additional power, and is quickly and easily adjusted to vary the cut-off position with respect to the length of wire remaining for the next 20 heading operation.

The accompanying drawings represent an illustrative embodiment of the invention, in which Fig. 1 is a plan view showing the invention applied to a three-die machine of the 25 type disclosed in copending application Serial No. 237,423, filed December 3, 1927; Fig. 2 a transverse sectional elevation taken on line II—II, Fig. 1, showing the dies and cut-off mechanism; Fig. 3 an elevational 30 view of the cut-off mechanism in position similar to that shown in Fig. 2; Fig. 4 a plan sectional view taken on line IV—IV, Fig. 3; Fig. 5 a vertical section taken on line V—V, Fig. 4; Figs. 6 to 8 plan, side and 35 end views of a forming die; Fig. 9 a view of a nail produced by the machine shown in Fig. 1; Figs. 10 to 12 plan, side and end views of a cut-off knife; Fig. 13 a transverse sectional elevation similar to Fig. 2 showing a 40 modified cut-off mechanism; Fig. 14 an enlarged elevational view of the modified cut-off mechanism shown in Fig. 13; Fig. 15 a plan view of the mechanism shown in Fig. 13; and Fig. 16 a vertical section taken on line 45 XVI—XVI, Fig. 15.

Although not limited thereto, the invention is particularly applicable to nail-machines used for making blunt-pointed, truncated tips, such as are illustrated in U. S. Patent No. 1,466,676, issued September 4, 50 1926, to H. S. Stronach, et al. The tips of these nails are such that there has been difficulty in making forming dies which would themselves shape the tip properly and also sever the nail. To secure that result, the machine of the application above referred to provides one of the forming dies with a cut-off knife positioned to sever the wire as it is gripped by the dies. 55

That construction requires that one of the 60 three dies used must be of special form. The special die which carries the cut-off knife must be made with considerable accuracy. The special dies, and the knives thereon referred to, are sometimes damaged, which 65 delays production and increases costs. Furthermore, the cut-off knives must be accurately set in order to produce high quality nails, and they require frequent attention. The present invention improves on the said 70 prior construction by providing means independent of the forming dies intermediate the dies and heading block, which operate in coordination with the dies to sever the nails when they are engaged by the dies. This 75 means preferably comprises a reciprocating cutter actuated by one of the die-actuating means.

By way of illustration the invention is shown applied to the nail forming machine so described and claimed in the said copending application. This machine comprises a frame 1, Fig. 1, a transverse crank shaft 2 journaled for rotation therein, and three longitudinal shafts 3, 4 and 5 journaled in 85 suitable bearings. Shafts 3, 4 and 5 are parallel to one another and are disposed preferably at 120 degree intervals about a common point. Spiral pinions 6 and 7 mounted on shaft 2 mesh with gears 8 and 9 respec- 90

tively carried by shafts 3 and 4. Shaft 5 is driven by means of a pinion 10 carried by shaft 3, an idler gear 11, and a gear 12 mounted on one end of shaft 5. The gears are selected to drive the shafts 3, 4 and 5 at equal speed. The crank shaft is driven by means of a fixed pulley 13.

The machine is also provided with wire feed mechanism including a reciprocating feed rod 14 eccentrically connected at one end to the crank shaft and at the other to a feed lever 15 which actuates a wire feed and straightening mechanism indicated generally by the numeral 16. The action of this feeding mechanism will be understood by those skilled in the art. Wire nail stock 17 is advanced by the feed mechanism 16 through a die block assembly 18 to a heading block or die 19. The heading block is preferably of the commonly used type which grips the wire during the heading operation and then releases it for advancement. A crank 20 mounted on crank shaft 2 is connected to a connecting rod 21 which reciprocates a hammer 22 in front of the heading block opening 23.

Each of the shafts 3, 4 and 5 is provided with an eccentric 24 connected to a die holder 25 which moves in a guide 26. Adjustably mounted in the forward end of each die holder 25 is a tip-forming die 27. The eccentrics 24 may be adjusted axially along their shafts and the guides 26 correspondingly adjusted along the supporting frame 1 to form different types of nails. The lugs 26' or the guides 26 interfit in guideways on the frame, as shown in Figure 2, to properly maintain the guides in adjusted position. The cut off mechanism, to be described hereafter, is also adjustable so as to be maintained in proper cooperative relation with the dies. The three dies 27 are identical and they are preferably shaped in the manner shown in Figs. 6 and 7, to form a blunt, three-faced tip T on the nail N, Fig. 9. Like the shafts which actuate them, the die holders and dies are disposed at angles of 120° about a common point, namely the axis of the wire stock 17. Inasmuch as the shafts rotate at substantially equal speed, the tip-forming dies will be radially reciprocated in a common plane transverse to the axis of the wire, and their action is synchronized so that they engage the wire substantially simultaneously.

The nail-stock severing mechanism according to the invention is mounted independently of the tip-forming dies, to be actuated in synchronism with the operation thereof. The embodiment illustrated in Figs. 2 to 5 comprises a guide block having a base portion 28 supported on die block assembly 18 and a vertical portion 29 provided with a dovetailed groove 30 in which a correspondingly shaped knife holder 31 may be reciprocated. A cut-off knife 32 is adjustably dis-

posed in the lower end of knife holder 31, preferably in a dovetail groove, as seen in Fig. 4. It may be held in fixed position therein in any suitable manner, as for example by a set screw 33. An enlarged view of the knife is shown in Figs. 10 to 12. The cutting tip is preferably formed by chamfering the end to form a blunted tip 48, seen in Fig. 11.

It is preferable to permit the knife holder to move downwardly close to the heading block, in order to permit the use of a relatively short knife. The thrust block 49 is, to this end, recessed at 34, this recess being deep enough to permit the adjustment of guide block 29 toward and away from the heading block, whereby to vary the length of wire which remains in front of the heading block after a nail has been severed to be affected by the next heading operation. This adjustment may suitably be obtained by providing parallel slots 35 on each side of the guide block base 28. Guide bolts 36 are disposed in these slots and extend into the anvil block. The guide block may be clamped in any desired position by lock nuts 37. In order to provide accurate adjustment of the knife position, the base portion of the guide block is tapped from the rear and threaded to receive a screw 38, the rear end of which is provided with collars 39 which ride on each side of a supporting saddle 40.

The knife holder 31 and knife 32 may be reciprocated in any suitable manner, and this may be accomplished by pivotally connecting the outer end of knife holder 31 to a rocker lever 41, one end of which carries a follower 42 which rides on a cam wheel 43. Cam wheel 43 is carried by one of the die-actuating shafts, in this case that indicated by the numeral 4. Intermediate the follower and this connection, lever 41 is pivotally connected at 44 to a fulcrum support 45 rigidly mounted on the frame 1. The other end of lever 41 is connected to a coil spring 46 mounted in any suitable manner. The tension of the spring holds follower 42 on cam wheel 43. Cam wheel 43, as shown in Fig. 2, is substantially circular except for a land 47 of relatively small extent. So long as follower 42 rides on the circular part of the cam wheel, lever 41 remains stationary in its horizontal position and the knife is elevated. When land 47 meets the follower, the lever is rocked about its fulcrum support against the tension of the spring, the knife holder is lowered, and the knife is brought into contact with the wire.

The operation of the machine is as follows: Assuming the heading die to have gripped the wire, rotation of crank shaft 2 advances the connecting rod and hammer until the latter strikes the projecting end of the wire and upsets it, to form the head of the nail. During this time, rotation of shafts 3, 4 and 5 has moved the forming dies to their outermost po-

sition. The connecting rod now begins to retract the hammer, the heading die opens to release the wire, and the headed wire is advanced to the proper nail length by the feeding mechanism. Simultaneously, the die-holders and forming dies 27 are advanced at a uniform rate by shafts 3, 4 and 5, and as the hammer moves to its fully retracted position, they grip the wire.

During these operations, follower 42 has been moving over the circular part of cam wheel 43, which is so disposed on its shaft that land 47 does not strike the follower until the dies grip the wire. Thus during all of the preceding interval, knife holder 31 and knife 32 have remained stationary. When the dies grip the wire, however, land 47 rocks lever 41 and the knife is forced downwardly with a quick motion, severing the wire immediately adjacent the dies 27. The dies continue to move inwardly to squeeze the severed end and form the nail tip. When the follower leaves land 47, the spring returns lever 41 to its knife-elevating position. The tip-forming dies 27 retreat, the heading block grips the wire, the hammer advances, and the cycle is repeated.

Figs. 13 to 16 show a modified form of cut-off mechanism applied to the machine described in connection with the preceding embodiment. In this form a cut-off knife 32a is carried by a knife holder 50 reciprocable in a guide block having a body portion 51 and a base portion integral therewith comprising spaced arms 52 adjustably connected in any suitable manner to heading block assembly 18a. The cut-off knife and general disposition of these parts are similar to those previously described.

The body portion of the guide block is provided with a dove-tailed guideway for the knife holder, which may be lined with brass slides 53, if desired. The lower knife-receiving portion of knife holder 50 is of the same shape as the guideway, and the knife is frictionally retained in a dovetail groove, as seen in Figs. 14 and 16. The upper portion of the knife holder is preferably formed as a cylindrical shaft 54 threaded to receive a nut 55. A coil spring 56 disposed over shaft 54 and seated between nut 55 and a cover plate 57 connected to the guide block, normally urges the knife holder and knife upwardly away from its wire-severing position.

As in the preceding embodiment, tip-forming dies 27a are reciprocated through eccentrics 24a by shafts 3a, 4a, and 5a rotatably mounted in bearings 58 carried by frame 1a, and the cut-off mechanism is actuated by a cam wheel 59 mounted on one of these shafts. The cam wheel is circular except for a land 59a. In the embodiment shown, this wheel is mounted on shaft 3a, part of the eccentric being broken away for clarity of illustration.

The upper cap of bearing 58 for this shaft

is formed to provide an upwardly and inwardly extending bifurcated bracket 60, Figs. 13 and 15, and a cut-off lever 61 is pivotally supported therein by a pin 62. A cam follower 63 is mounted in one end of this lever, to run on cam wheel 59. A threaded pin 64 in the other end of the lever bears against the free end of knife holder shaft 54. The mechanism is adjustable through nut 55 and pin 64 which is locked in any desired position by a nut 66.

The general operation of the machine embodying the modified cut-off construction is similar to that previously described. Spring 56 normally holds knife 32a in retracted position, and follower 63 bearing on cam wheel 59 absorbs the thrust, so that the cut-off lever remains stationary as long as follower 63 travels on the circular portion of cam wheel 59. When rotation of the shafts has brought the tip-forming dies to wire-engaging position, land 59a strikes the follower and rocks the cut-off lever against the spring tension, to force the knife holder downwardly, causing the knife to sever the wire. Upon further rotation of the shaft the land leaves the follower, and spring 56 returns the mechanism to retracted position.

In this form the knife is frictionally held in the knife-holder, and as it wears away it may be maintained at the proper length by a backing plate pushed in a slot 65, Fig. 14, provided in the knife-holder.

Although the invention has been described in connection with a machine for making nails having a truncated triangular pyramid tip, its use is not limited thereto. It can be applied to other types of machines.

A particular advantage of the invention is that through its use identical tip-forming dies may be used. This permits standardization and eliminates the expense attendant upon the production of special knives. It also eliminates the difficulties and disadvantages present in the use of a combined cut-off knife and forming die. Such dies are formed of expensive tool steel, and are usually made by skilled toolmakers. Their life is comparatively short, so any saving in cost of making or by longer life after making is of material importance.

We claim as our invention:

1. In a nail making machine, a heading block, means for feeding wire thereto, tip-forming dies disposed in a common plane ahead of said heading block and radially reciprocable with respect to the wire, means positively actuating each die, the dies forming the tip of the nail into a truncated pyramid, a reciprocating cut-off knife disposed between said heading block and dies, the knife forming the end of the truncated pyramid, and mechanism associated with one of said die-actuating means actuating said knife in timed relation with said dies to

sever the nail after engagement by the dies but before the tip has been fully formed, said die and knife being adjustable longitudinally of said heading block.

- 5 2. A nail making machine, comprising in combination a frame, a heading block, means for supplying wire to said block, parallel shafts mounted in spaced radial relation to the wire for rotation in said frame, a reciprocating tip-forming die carried by each of said shafts, a cut-off knife mounted for reciprocation intermediate said dies and block, a cam wheel mounted on one of said shafts, and rocker mechanism associated with said 10 cam wheel and knife, said dies being synchronously reciprocated in a common plane and adapted to form a truncated pyramidal tip on one end of the nail, and said knife being adapted to sever the wire after its engagement by said dies.

3. In a machine for making nails having a blunt, three-faced tip, the combination of a frame, a heading block and heading mechanism, wire-feeding means, three shafts rotatably mounted in said frame, three tip-forming dies reciprocated one by each of said shafts and disposed symmetrically about the wire in a common plane ahead of said block, and cut-off mechanism comprising a guide 25 block, a knife-holder reciprocable therein, a knife carried by said holder, a lever connected to said holder and rockable about a fixed point, and a cam wheel mounted on one of said shafts and adapted to actuate said 30 lever, said knife being adapted to sever the wire as soon as it is engaged by said dies.

4. A nail making machine according to claim 3, said dies and said cut-off mechanism being adjustably mounted for varying the 40 amount of wire left exposed in the heading block for a succeeding heading operation.

5. In a nail making machine, the combination with a heading block, heading mechanism, a plurality of angularly-disposed rotatable shafts, positively-reciprocated dies 45 synchronously actuated one by each of said shafts and adapted to engage wire passed through said block to form a tapered truncated nail tip, of wire cut-off means operable 50 independently of and located adjacent said dies and comprising a guide block disposed between said dies and heading block, a knife-holder reciprocable therein, a knife removably mounted on said holder, and means actuating said knife to sever the wire as it is gripped by the dies, said guide block and 55 said reciprocating dies being adjustably mounted to permit movement to and from the heading block, whereby to vary the length of 60 the several and untipped portion of the wire remaining for a subsequent heading operation.

6. In a machine for making nails having a blunt, three-faced tip, the combination of a 65 frame, a heading block and heading mecha-

nism, wire feeding means, three shafts rotatably mounted in said frame, three tip-forming dies symmetrically disposed about the axis of the wire ahead of said heading block and reciprocated one by each of said shafts, cut-off mechanism independent of said dies comprising a guide block, a knife holder reciprocable therein, a cut-off knife carried by said holder, a spring cooperating between said holder and guide block to urge the knife away from said wire, and knife-actuating means, said means comprising a pivotally mounted lever, a pin carried by one end of said lever and bearing against the knife holder, a follower carried by the other end of said lever, and a cam wheel mounted on one of said shafts to run against said follower, said cam wheel rocking said lever to reciprocate the cut-off knife in synchronism with the action of said dies.

7. In a machine for making nails having a blunt, three-faced tip, the combination of a frame, a heading block and heading mechanism, wire-feeding means, three parallel shafts rotatably mounted in said frame, three tip-forming dies symmetrically disposed about the axis of said wire ahead of said heading block and reciprocated in a common plane one by each of said shafts, wire cut-off mechanism independent of said dies comprising a guide block carried by said heading block, a knife holder reciprocable therein, a cut-off knife removably mounted on said holder, a spring cooperating between said guide block and holder to urge said knife away from said wire, and knife-actuating means, said means comprising a bracket formed on a bearing for one of said shafts, a lever pivotally mounted in said bracket, a pin carried by one end of said lever and bearing against said knife holder, a follower rotatably mounted in the other end of said lever, and a cam wheel running against said follower mounted on said shaft adjacent said bearing, said lever being rocked by said cam to move the knife to cutting position in synchronism with the action of said dies.

8. In a nail making machine, the combination of head forming mechanism including gripping dies, means for feeding wire to said mechanism, a plurality of positively-reciprocated tip-forming dies disposed radially about the wire, a cut-off knife associated with said mechanism, and means synchronously actuating the heading mechanism, tip-forming dies and cut-off knife, the gripping dies being open when the wire is engaged by the tip-forming dies, and the wire being severed immediately after it is engaged by the tip-forming dies.

9. In a nail making machine, the combination of head forming mechanism including gripping dies, means for feeding wire to said mechanism, a plurality of positively-reciprocated tip-forming dies disposed radially about the wire, a cut-off knife associated with said mechanism, and means synchronously actuating the heading mechanism, tip-forming dies and cut-off knife, the gripping dies being open when the wire is engaged by the tip-forming dies, and the wire being severed immediately after it is engaged by the tip-forming dies.

about the wire, a rotatable shaft actuating each of said dies, a cut-off knife disposed between the heading mechanism and the tip-forming dies, means associated with one of 5 said shafts operating said knife to sever the wire when engaged by the tip-forming dies, the heading mechanism, tip-forming dies and knife being synchronously actuated, and the gripping dies being open during the tip- 10 forming operation.

In testimony whereof, we hereunto sign our names.
